POWER INSERT FOR INTERNAL COMBUSTION ENGINES

Raphael Hollingsworth, Richland, Iowa

Application May 19, 1954, Serial No. 430,860

4 Claims. (Cl. 123—191)

This invention relates to turbulent and compression ratio increasing insert rings and is an improvement of my compression ratio increasing insert rings for internal combustion engines, issued April 27, 1954, and bearing Patent No. 2,676,580.

My ring disclosed in the above patent was primarily for reducing the explosion chamber thereby increasing the compression ratio and was applied to engines of low compression and having sufficient clearance between the top dead center and the cylinder head. Also the insert ring was so designed as to handle overhead valves and be prevented from undesirable rotation. While the insert ring was most successful, it did not sufficiently mix and agitate the gases entering the combustion chamber.

Therefore, the principal object of my invention is to provide an insert ring for combustion engines that causes great turbulence of the fuel charge entering the cylinder, thereby successfully mixing the fuel charge and more uniformly depositing the same in the cylinder at time of firing.

A further object of this invention is to provide a fuel mixing insert ring that is easily and quickly installed.

A still further object of my invention is to provide a turbulence causing insert for combustion engines that has no moving parts.

Still further objects of my invention are to provide a cylinder insert ring that is economical in manufacture and durable in use.

These and other objects will be apparent to those skilled in the art.

My invention consists in the construction, arrangement, and combination of the various parts of the device, whereby the objects contemplated are attained as hereinafter more fully set forth, specifically pointed out in my claims, and illustrated in the accompanying drawings, in which:

Fig. 1 is a top plan view of my insert ring,

Fig. 2 is a cross sectional view of the device taken on line 2—2 of Fig. 1, and

Fig. 3 is a side sectional view of the ring taken on line 3—3 of Fig. 1 and installed in the combustion area of an overhead valve combustion engine.

Referring to the drawings I have used the numeral 10 to designate the ring generally which is made from any suitable material such as cast iron or the like. A flange 12 is provided at the upper outside edge of the ring. This flange engages the cylinder block 14 at its free end as shown in Fig. 3. The ring is also provided with a channel 16 which embraces the inner end of the spark plug 18 as shown in Fig. 3. By embracing the spark plug with the ring in this manner, the ring is positively secured against rotation within the cylinder. The ring is also held to some extent against rotation with the ring against the cylinder walls. The top of channel 16 is connected to the top of the ring by the slot 20 which allows space for compressing the ring as it is inserted into the cylinder. The compressed ring exerts an out-

2

ward pressure on the cylinder walls when it is in position which also aids in securing the ring against any movement relative to the cylinder. A still further feature of my present invention is the crescent shaped valve clearance well 22 which is formed in the top of the ring at an appropriate point for the particular engine. By the use of this well, the ring may be used without interfering with valves that are set close to the edge of the cylinder as the intake valve designated 24 in Fig. 3.

10 The length of the ring must be less than the distance between the piston 26 and the cylinder head 28. The numeral 30 designates the gasket which is inserted between the cylinder head and the cylinder block. Obviously, the thickness of the ring will reduce the combustion area, thereby increasing the compression ratio. The normal use of the ring requires it to be inserted into the cylinder flange end last. The flange engages the top of the cylinder to prevent the ring from descending too far into the cylinder. The piston, however, is just as large and moves just as far as it ever did. Consequently, the same amount of combustible mixture is forced into a smaller space than was true before my ring was inserted. Clearly the extent of compression of the gaseous mixture is increased. The engine compression ratio is increased, therefore, and an engine designed for use with fuels having low octane ratings is adapted to make efficient use of high test fuels.

From the foregoing it will be noted that the fuel charge will enter the combustion chamber at a velocity greater than if my ring were not present. This fact is one of the reasons for my present invention of providing mixing fins as an integral part of my compression ring. Thus there is a cooperative combination between the ring disclosed in my issued patent and my turbulence producing baffle fins which I will now disclose in detail. Adjacent the half-moon cut-away portion 22 and near its bottom plane, I form a horizontal inwardly curved bridge 27 that bows inwardly as shown in Fig. 1. The open space between this bridge and the inside wall of the ring is designated by the numeral 28. On the side of the bridge closest to the cylinder center, I have formed a plurality of spaced apart baffle vanes 29, as shown in Fig. 2. These baffle vanes may be of any suitable design, construction or arrangement. In the drawings I show them as elongated hooked flat fingers radially extending from the periphery of the bridge member. They start at their bases, approximately horizontal and then are twisted laterally and upwardly until their outer ends are almost vertical. When the valve 24 is opened or lowered, these finger baffles loosely embrace or cage the inner curved side of the valve, and the fuel charge entering must substantially pass through the opening 28 or between these angle baffle fingers 29. Obviously due to the curvature of the radially inwardly extending vanes and their curved collective position in the entering gas stream, great turbulence will be experienced by the fuel charge. This vortex of the fuel, will uniformly mix it, and direct it in violent motion to all areas of the combustion chamber.

Some changes may be made in the construction and arrangement of my power insert for internal combustion engines without departing from the real spirit and purpose of my invention, and it is my intention to cover by my claims, any modified forms of structure or use of mechanical equivalents which may be reasonably included within their scope.

I claim:

1. In a device of the class described, a ring member adapted to be inserted in the combustion chamber of an internal combustion engine having an inlet valve opening into said chamber; said ring member having a cut away portion adapted to be positioned adjacent and di-

rectly under the inlet valve of such combustion engine when installed for providing operating room for such a valve, and a plurality of upwardly curved and twisted flat fingers carried by said ring member and in the vicinity of said cut away portion to give twisting turbulence to a fuel charge passing the intake valve of the engine to which the device is installed.

2. In a device of the class described, a ring member adapted to be inserted in the combustion chamber of an internal combustion engine having an inlet valve opening into said chamber, said ring member having a cut away portion adapted to be adjacent and directly under the inlet valve of such combustion engine when installed for providing operating room for such a valve, and a plurality of flat and upwardly curved hook-like fingers carried by said ring member adjacent said cut away portion, each finger throughout substantially its entire length being partially twisted about its axis to provide a fuel deflecting surface, whereby to give twisting turbulence to a fuel charge passing the inlet valve of the engine to which the device is installed.

3. In a device of the class described, a ring member adapted to be inserted in the combustion chamber of an internal combustion engine having an inlet valve opening into said chamber; said ring member having an upper cut away portion adapted to be adjacent and directly under the valve of such combustion engine when installed for providing operating room for such a valve, an inwardly extending bar-like bridge secured to said ring member at its ends at the site of said cut away portion and positioned beneath said inlet valve opening, and a plurality of inwardly extending spaced apart and elongated flat fingers attached to said bridge, each finger being partially twisted about its axis to provide fuel deflecting

surfaces, whereby to give a twisting turbulence to a fuel charge passing the inlet valve of the engine to which the ring is installed.

4. In a device of the class described, a ring member adapted to be inserted in the combustion chamber of an internal combustion engine having an inlet valve opening into said chamber; said ring member having an upper cut away portion adapted to be adjacent and directly under the valve of such engine when installed for providing operating room for such a valve, an inwardly extending bar-like bridge secured to said ring member at its ends at the site of said cut away portion and spaced from said ring and positioned beneath said inlet valve opening, and a plurality of inwardly extending spaced apart and elongated flat fingers attached to said bridge, each finger being partially twisted about its axis to provide a fuel deflecting surface, and the free inner ends of said fingers being curved upwardly to a plane above the bottom plane of said cut away portion, whereby to give twisting turbulence to a fuel charge passing the inlet valve of the engine to which the device is installed.
